Filed Mar. 12, 1969, Ser. No. 16,214

Term of patent 14 years

Int. Cl. D8—02

U.S. Cl. D8—53

FIG. 2

FIG. 4

FIG. 1

FIG. 5

FIG. 3

FIG. 1 is a front elevational view of a pair of scissors showing my new design, in closed condition;

FIG. 2 is a top plan view;

FIG. 3 is a rear elevational view, in open condition;

FIG. 4 is a sectional view on line 4—4 of FIG. 1; and

FIG. 5 is a sectional view on line 5—5 of FIG. 1.

The characteristic feature of the design resides in the particular animal representation forward of the handles and on the blades.

I claim:

The ornamental design for a pair of scissors, substantially as shown and described.
